UNITED STATES PATENT OFFICE.

THOMAS CARROLL, OF OAKWOOD, OHIO, ASSIGNOR TO THE NATIONAL CASH REGISTER COMPANY, OF DAYTON, OHIO, A CORPORATION OF OHIO, (INCORPORATED IN 1906.)

FARE-REGISTER.

1,143,747.

Specification of Letters Patent. Patented June 22, 1915.

Application filed November 24, 1909. Serial No. 529,734.

To all whom it may concern:

Be it known that I, THOMAS CARROLL, a citizen of the United States, residing at Oakwood, in the county of Montgomery and 5 State of Ohio, have invented certain new and useful Improvements in Fare-Registers, of which I declare the following to be a full, clear, and exact description.

This invention relates to fare registers and is mainly designed to furnish a satisfactory accounting device especially adapted for use on so-called "pay-as-you-enter" conveyances, though its utility is not limited to this field. On conveyances of this 10 type conductors or other collectors of fares, are stationed at the entrance of the vehicle, usually a street car, and receive fares as the passengers board the cars. In cars of other types, where fares are collected by passing through the car, the register must be so constructed as to be operable from any part of the car, and because of the necessary complication of connections it is difficult to provide a machine operable from 15 any point, but which will at the same time permit the separate registration and indication of several classes of fares. In the case of "pay-as-you-enter" cars, however, the objection noted, is not found, as the collector of fares is not required to move about the car, and thus may be provided with an 20 easily operated machine which will have capacity for registration and indication of a considerable number of different classes or 25 values of fares.

It is the main object of the present invention to provide a fare register and indicator especially adapted for this type of conveyance, having separate keys or levers for 30 each class of fare, the single operation of which will separately register and indicate several classes of fares.

The machine is also provided with means for printing the total of amounts accumulated by the different registers or counters and also with paper feeding mechanism which operates each time printing is done, therefore providing means for successively printing totals in different lines on a single 45 sheet of paper. With each printing operation the counters are simultaneously reset.

The machine is also provided with a total counting device which counts the total number of all fares registered, and separate nor-

mally locked means are provided for resetting this total counter.

Indicating mechanism is provided which indicates each fare according to its class when the fare is registered.

Various mechanical devices are comprised 60 in the machine which compel the correct operation of the machine, as is pointed out in the ensuing description.

With these and incidental objects in view the invention consists in certain novel features of construction and combinations of parts, the essential elements of which are set forth in appended claims and a preferred form of embodiment of which is hereinafter described with reference to the drawings 70 which accompany and form part of the specification.

Of said figures: Figure 1 is a front elevation of the fare register, with the cabinet shown in section. Fig. 1^A is a view of a 75 portion of an illustrative form of detail strip showing records printed thereon. Fig. 2 is a rear elevation with the cabinet omitted. Fig. 3 is a right side elevation with the cabinet omitted. Fig. 4 is a transverse vertical section taken on the line 4-4 of Fig. 1. Fig. 5 is a detail of the printing mechanism. Fig. 6 is a detail of a full stroke device which compels the complete operation of any operating lever when depressed. 85 Fig. 7 is a detail illustrating the manner in which the indicators are set. Fig. 8 is a detail of the ink pad.

The machine is provided with a plurality of levers, the depression of any one of which 90 will cause a complete operation of the machine by registering a fare and elevating an indicator. Each lever operates a separate counter. These counters may be designated as follows: Five-cent, three-cent, ticket, 95 transfer, and pass. The operating levers are indicated in the drawings by numeral 1, and are all loosely pivoted on a shaft 2. Each lever extends in under one of the arms 3 of the indicators 4 rearwardly of the shaft. 100 The indicators are mounted in guide ways 5 and 6 and are slidably therein and are normally drawn to their lower position by springs 7. When any lever 1 is depressed its corresponding indicator is raised so that 105 its respective indication will come between the openings 8 and 9 in the cabinet 10 (Fig. 4). Each indicator is lettered on the front

and rear sides so that it may be read either from the front or the rear of the machine. Each indicator is provided with a lug 11 which co-acts with a spring pressed pawl 12, 5 for the purpose of holding the indicator in its exposed position. The pawl 12 carries about midway of its length a pawl 13 which upon the rise of any indicator is first engaged by the lug 11, before the lug engages the pawl 12. The engagement of the lug 11 with the pawl 13 causes the pawl 12 to be rocked well clear of the lug 11 of whatever indicator is already in exposed position, permitting such indicator to lower before the 10 shoulder 11 of the rising indicator engages the pawl 12. A spring for urging the pawl 12 toward the indicators is indicated at 14, and such spring impelled movement of the pawl is limited by the edges 15 of the indicators. The pawl 12 is of course rocked away from the indicator lugs when engaged by one of the shoulders 11 and would thus release any indicator which is in exposed position regardless of the pawl 13 but in such 15 case the shoulders 11 would all have to be in the same vertical plane, as otherwise an exposed indicator might not be released upon the rise of another indicator. By providing the pawl 12 with the additional pawl 13, the 20 shoulders 11 may vary within wide limits without preventing the correct operation of the indicator mechanism. It may be seen that the pawl 13 will not prevent the lowering of an indicator as it is free to rock downwardly against the tension of its spring 16. The rearward parts of the levers 1 extend through slots 17 in a guide plate 18. The plate 18 carries key stops 19 which are pivoted to the plate at 20 to be free to rock a certain extent, but are limited in their 25 rocking movement by the two end levers 21 and 22 which extend across the beveled edges 23 of the two end key stops. The total amount of free movement between the key 30 stops is just sufficient to permit the passage of one lever 1 and it is therefore impossible to depress more than one of these levers at a time. Each lever 1 is provided with a slot 24 35 (Fig. 7) into which the arm 3 of its respective indicator normally extends. The slot 24 is normally partly closed by a slide 25 which is carried by the lever 1, by means of the pins 26 which extend from the lever through a slot 27 in the slide. A spring 28, 40 extending from a pin on the lever 1 to a pin on the slide, normally urges the slide forward, but when the lever is in its normal position, the slide is prevented from moving forward by a rod 29 which is carried by the machine side frames 30 and 31 and extends across the forward edges 32 of all of the slides 25. The slides are also provided with small shoulders 33 which upon the upward movement of the rearward part of the

lever 1 engage the arms 3 of the indicators. Therefore the slide is prevented from moving forwardly upon the depression of the forward end of lever 1. Upon the depression of a lever 1, provided such lever had not been depressed on the last previous operation of the machine, it will carry its respective indicator slightly above the position to which it comes to rest when its lug 11 rests on the pawl 12, but if upon the next operation of the machine the same lever 1 is depressed the arm 3 of its respective indicator will not be in the path of the shoulder 33 of the slide 25. Therefore the slide 25 will spring forwardly when clear of the rod 29 and then does not obstruct the opening 24 in the lever, as indicated by broken lines in Fig. 7. By this construction when the rear of the lever 1 reaches its highest position it will not strike the arm 3 of its respective indicator and for this reason not cause a needless vibration of the indicator. The strokes of the levers 1 are limited by the tie bars 34 and 35.

Each lever 1 is connected by a link 36 to the carrying frame 37 of a multipronged pawl 38 of its respective counter 39. The frames 37 are loosely pivoted on a shaft 40 and the pawls 38 which are pivotally carried by the frames are adapted to engage ratchets 41 when their respective carrying frames 37 are rocked downwardly upon the depression of a lever 1. Each ratchet 41 is fixed to a type wheel 42 loosely journaled upon the shaft 40, but normally prevented from rotating in one direction by a retaining pawl 43 (Fig. 4). Any desired transfer between the counter wheels may be employed, that illustrated being of the well known deep-notch type, and not needing particular description.

The total counter is indicated by numeral 45. Its retaining pawls are indicated at 46 and a multipronged pawl by means of which the counter is actuated is indicated at 47. The pawl 47 is carried by a frame 48 which by means of the link 49 is connected to a key actuated frame 50. The frame 50 is composed of two arms 51 pivoted on a rod 54 and having a connecting bar 52, which 115 passes over the upper edges of all of the levers 1 and accordingly when any lever 1 is depressed the frame 50 will be rocked upwardly causing "one" to be added to the counter 45. A spring 53 (Fig. 1) which is 120 coiled around the rod 54 upon which the frame 50 is pivoted urges the frame 50 to its lower position and therefore serves to return a depressed lever 1 to its initial position. The rod 52 by coacting with lugs 54^a (Fig. 4) of the levers 1 which are not depressed serves to prevent their depression during the time, upwardly and returning. By this means, the rod 52 and lugs 54 serve the same purpose as the stops 19 being an 130

additional precaution against an improper operation of the machine.

The wheels of the counter 45 are provided with characters which may be read from the front of the machine whereas the counters 39 are provided with reversed type characters suitable for printing upon a detail strip 55.

The rod 52 extends through a notch 56 (Fig. 3) in a lever 57 at the right of the machine. The lever 57 is loosely pivoted upon the shaft 2 and at its rear end is forked for the purpose of engaging a sliding rod 58 at an annular groove 59 in the same. Because of this arrangement the depression of a lever 1 will cause the slide rod 58 to be moved upwardly and then returned to its initial position. The rod 58 is guided in its vertical movement by lugs 60 and 61 through which it passes, and carries a member 62 provided with two rows of ratchet teeth 63 and 64 which co-act respectively with pawls 70 and 71. These pawls are mounted on pins extending from the side frame 81 and are spring pressed as shown toward their respective ratchet teeth of the member 62. It may be seen from Fig. 6 which is a top plan view of this full stroke mechanism, that the rows of teeth 63 and 64 are not both in the same vertical plane with their respective pawls but the member 62 is provided at bottom and top with inclined surfaces 65 and 66 for co-acting with the inclined lugs 67 and 68 of the lugs 60 and 61 so that when the member 62 reaches the limits of its upward and downward strokes it will be partly rotated so as alternately to present the rows of teeth 63 and 64 to their respective pawls. When the member 62 is in its lower or home position the teeth 63 will be in line with the pawl 70. Therefore it is possible to move the member 62 as is necessary in order to operate the machine, but it is impossible to return the same before it has reached its upper position clear of the pawl 70. When the member 62 engages the lug 68 it is swung in such position that the teeth 64 are engaged by the pawl 71 upon the lowering of the member 62 which permits the member 62 to lower but prevents it from being returned upwardly until it has reached its initial lower position. The idea of employing a so-called full stroke device in machines of this general type is well known, but this particular form shown has the advantage of requiring much less lost motion than is usual. In devices having reversing pawls or the like a considerable movement of the arrested element is required to cause the reversing and this part of the movement is not controlled as to direction, but with the present form, the reverse may take place almost instantly.

From the preceding description it will be seen that the machine is well adapted to

use on the type of conveyance specified. The levers are readily grasped and operated as required, and each operation of a lever adds one unit to the reading of the corresponding counter and elevates the corresponding indicator, so that the passenger may readily see whether his fare has been registered.

Printing and resetting mechanism.—The machine as thus far described is operative, but in order to use the counter accumulations, they would need to be read and transferred to some record by hand. In order to obviate this operation and to prevent mistakes or fraud in transferring the counter readings, a printing device has been designed, constructed so that at the end of a trip or other period, the totals on the counters may be automatically printed on a strip of paper concealed inside the machine, and the counters reset to normal zero reading. The means for causing such total printing and resetting may be under the control of the fare collector, but he will desirably not have access to the record strip, which will be withdrawn from the machine at the end of any desired period by some inspector or other trusted employee. After such printing operation the record strip is automatically fed a short distance so that the next impression may be on a different line.

The detail record strip 55 is led from a supply roll 72 around a platen 73, upwardly between the roll 74 and the platen and past a knife edge 75. The lower part of the platen is encircled by a paper guide 76.

The supply roll 72, the platen, and related mechanism are all carried by frame arms 77 which are supported by a shaft 78 journaled in the two machine side frames 30 and 31. The frame arms 77 are tied together by the shaft 79 of the platen roll and the knife 75. The right hand frame arm 77 carries a stud 80 which extends into the cam race 81 of a disk or cylinder 82. In order to take an impression of the total which has been accumulated by the different counters, the cam 82 is rotated in a clockwise direction (Fig. 5) causing the frame arms 77 to rock bringing the platen 73 into contact with the type wheels of the counters. The cam race 81 is so formed that the platen 73 will first be carried far enough toward the type wheels to press an ink pad 83 against the type wheels. It then causes the platen to rise slightly, permitting the withdrawal of the ink pad and then carries the platen into contact with the type wheels and so effecting the impression. The same cam 82 is provided with a race on its opposite side for the purpose of causing the ink pad 83 to be carried between the platen and type wheels at the proper time. The ink pad is carried by a strip of metal 84 which is pivoted on arms 85 fixed to the shaft 2. The right hand arm 85 is pivoted to one end of a pitman 86

which carries a roll 87 extending into the race 88 (Fig. 3) of the cam 82. A spring 111 (Fig. 4) which urges a plunger 112 upwardly into engagement with a flat surface 113 of the strip of metal 84 serves to hold the ink pad in the desired horizontal plane with respect to the type carriers. The strip of metal 84 may be rocked forwardly around its pivot so that the plungers 112 will engage the flat surfaces 114 of the ears of the strip of metal 84 and hold the ink pad holder in its moved position. This is for the purpose of facilitating the removal of a pad for re-inking or for inserting a new pad. The pads are sewn to perforated metal strips as illustrated in Fig. 8, which strips are of suitable width for fitting within the grooves 115 of the ink pad holder 84.

The cam 82 is carried by a stub shaft 89 which is journaled in the side frame 31, and is provided with a key seat 90 into which a key may be inserted for the purpose of rotating the shaft. This shaft also carries a mutilated gear 91 which after an impression is taken meshes with a pinion 92 carried by the counter wheel shaft 40 and causes the rotation of this shaft. The shaft 40 is provided with a longitudinal groove which co-acts with small pawls carried by the counter wheels for the purpose of engaging such pawls upon the rotation of the shaft to cause a forward rotation of the counter wheels to their zero position. This is a well known construction for resetting counter wheels, and is illustrated in Fig. 4 of the drawings. The cabinet of the register is provided with an opening at 93 (Fig. 1) to permit the key by means of which the impression of the total is taken and the counter is reset, to be inserted. When returning the counters to zero, the shaft 89 is stopped at the proper point by a pawl 116 which co-acts for this purpose with a suitable notch in the periphery of the cam 82. The pawl 116 is urged into engagement with the notch in the cam by a spring 119 (Fig. 3).

In order to move the pawl away from the cam 82 to permit the counters to be reset again, after the machine has again been operated, the pawl is provided with an elongated slot 118 surrounding its pivot and a downwardly extending arm 117. This arm is engaged by the arm 57 upon the depression of one of the levers 1, causing the pawl 55 to be rocked rearwardly away from the cam 82. When in such position the pawl is drawn upwardly by the spring 119. It then does not prevent rotation of the cam 82 except after it has made a complete rotation.

60 The total counter 45 is reset in the same manner by a key which is inserted in an opening 94 in the cabinet. This opening, however, is normally covered by a shield 95 (Fig. 3) which is urged by a spring 96 away from the opening but is held in such

position by a hinged lid 961 when in its closed position. The lid when closed engages a rod 97 (Fig. 3) which is slidably mounted in a lug 98 and is pivoted to the shield 95 by a pin 99. Therefore in order 70 to reset the total counter the lid 961 must be unlocked and lifted upwardly. At such time the part of the strip upon which the totals are printed may be torn from the remainder of the strip at the knife edge 75. 75

A feeding device is provided for the strip 55 so that the same will be fed forwardly a certain amount after each impression. The feeding device comprises an arm 100 which is loosely pivoted upon the shaft 79 and at 80 its lower end is forked over a pin 101 which extends inwardly from the side frame 31. Because of this arrangement when the frame 77 is rocked to take an impression the arm 100 will first be rocked in the direction indicated by the arrow 102 causing a pawl 103 which is carried by the arm to move backwardly one tooth space with respect to a ratchet 104 which is rigid with the platen 73. Then upon the return of the frame 77, 90 the pawl 103 engages the ratchet and causes the same to rotate forwardly one tooth space thereby feeding the strip of detail paper 55.

Means are provided for locking the levers 1 against manipulation at the time a printing impression is taken and the counters reset. This means comprises a stop 105 (Figs. 3 and 5) which is pivoted to a stud 106 on the frame 31 and is provided with a shoulder 107 which by rocking the stop rearwardly comes into the path of the vertical full stroke rod 58 and prevents the upward movement of the same. The stop 105 is normally held out of the path of the rod 58 by a spring 108 which forces an end 109 of the stop 105 in a semicircular cut 110 in the periphery of the cam 82. By rotating the cam 82, the end 109 of the top 105 is forced out of the cut in the cam bringing the shoulder 107 over the rod 58. It is held in such position by the periphery of the cam until the cam arrives at its home position, when it again swings into the cut in the cam permitting the operation of the machine. 100 110

To operate the machine each fare is registered by depressing the proper lever 1 for the fare causing the respective counter to advance one unit and also the total counter 45 to advance one unit. At the completion of each trip, or period of time, the collector causes the printing of the total by rotating the shaft 89 which also causes the counters 39 to be reset. These records of the total fares collected by one or more operators are retained locked within the casing, access to the same being had only by an authorized inspector or other person provided with a key for unlocking the lid 961. 115 120

It will thus be seen that the machine though simple and easily operated is well 125

adapted to compel accuracy in collection of fares, and has means for readily taking off its records without liability to error.

While the form of mechanism herein shown and described is admirably adapted to fulfil the objects primarily stated, it is to be understood that it is not intended to confine the invention to the one form of embodiment herein shown and described, as it is susceptible of embodiment in various forms all coming within the scope of the claims which follow.

What is claimed is as follows:

1. In a machine of the class described, the combination with a plurality of counters and separate operating means for each of said counters, of a platen and resetting devices common to all of said counters, and common operating means for first bringing the counters and platen into co-operative relation for taking an impression from all of said counters upon a record strip and then operating the resetting devices simultaneously to reset all of said counters. 70
2. In a machine of the class described, the combination with a series of counters and means for operating said counters separately, of resetting devices for said counters, a platen, and means for moving it against all said counters simultaneously and a common operating device having connections for first moving said platen and then actuating said resetting device. 80
3. In a machine of the class described, the combination with a series of counters and means for operating said counters separately, of a resetting shaft for said counters, a printing platen, and means for moving it to take impressions from all said counters, an operating device, and a cam and a gear fast to said operating device and having connections respectively to said platen moving means and said resetting shaft. 90
4. In a machine of the class described, the combination with a series of counters, and a resetting shaft supporting the same, of means for separately operating said counters, a printing platen positioned to confront all said counters, an operating device having a cam and a gear fast thereto, and connections from said cam to move the platen to take printing impressions from said counters, and from said gear to rotate said resetting shaft. 100
5. In a machine of the class described, the combination with a series of counters, and means for operating said counters separately, of means for simultaneously resetting them, of a printing platen confronting all said counters, and a hand operated element having connections to operate said platen and thereafter to operate said resetting means simultaneously to reset all of said counters. 110
6. In a machine of the class described, the combination with a series of printing
- counters, and a corresponding series of keys for operating said counters separately, of a platen for taking impressions from all said counters, a bar operated by the keys and to which an operated key becomes locked, means for operating said platen, and devices controlled by said platen operating means for locking said key operated bar. 120
7. In a machine of the class described, the combination with a printing counter, and means including a key for operating said counter, of a platen and means for operating said platen to take an impression of the total on said counter, devices for presenting a second operation of said platen operating means, and connections controlled by the key for disabling said preventing devices. 125
8. In a machine of the class described, the combination with a series of printing counters, and means including keys for operating said counters separately, of a platen and means for operating it to take an impression of the total on all said counters, an arm for preventing a second operation of said platen operating means, and a bar controlled by all said keys and having connections to disable said preventing arm. 95
9. In a machine of the class described, the combination with a series of tablet bearing indicator rods each having a lug, of a supporting frame positioned to engage under the lug of any elevated indicator rod, and a by pass tripping frame pivoted to said supporting frame and positioned to be engaged by the lug of any indicator rod during its elevation. 100
10. In a machine of the class described, the combination with a series of tablet bearing indicator rods each having a lug, and means, such as key levers, for separately elevating said rods, of a supporting frame positioned to move under and support the lug of any elevated indicator rod, a by pass tripping frame pivoted to said supporting frame and positioned to be engaged by any of said lugs during their elevation, and a spring normally forcing said supporting frame into engaging position. 110
11. In a machine of the class described, the combination with a series of tablet bearing indicator rods each having a lug, and means, such as key levers, for separately elevating said rods, of a supporting frame comprising pivoted arms and a connecting bar positioned to move under and support the lug of any elevated indicator rod, and a by pass tripping frame pivoted to said supporting frame and normally having its cross rod engaging one of the arms of the supporting frame, said tripping frame being positioned to have its cross rod engaged by any of said lugs during their elevation. 115
12. In a machine of the class described, the combination with a key lever, and a plate mounted to slide thereon, and having upper 130

portions of graded height with an intermediate holding projection, and also having a depending camming portion, of a bar with which said camming portion normally engages, and a tablet bearing indicator rod normally resting on the higher of the graded portions of said slide and adapted to be elevated thereby.

13. In a machine of the class described, 10 the combination with a key lever, and a plate mounted to slide thereon, and having upper portions of graded height with an intermediate projection, of means for forcing said plate in one direction as the key lever 15 approaches normal position, a tablet bearing indicator rod normally resting on the higher of said graded portions, and adapted to be engaged by said projection as the key lever leaves its normal position.

20 14. In a machine of the class described, the combination with a series of indicator rods each having a lug projecting therefrom, of means for elevating said rods, a pivoted frame for supporting the elevated 25 rods by engaging the underside of the lugs thereon, and means, mounted upon the supporting frame and engaged by the lugs of the indicator rods, for rocking the supporting frame and thereby releasing the ele- 30 vated indicator rod.

15. In a machine of the class described, the combination with a series of indicators each having a lug projecting therefrom, of means for elevating said indicators, a frame 35 pivoted at one end, the other end of said frame being constructed to engage the underside of the lugs and hold the indicators elevated, and an additional frame approximately centrally mounted upon the supporting frame and engaged by the lugs of the indicator rods, for rocking the supporting frame and thereby releasing the elevated indicator.

16. In an indicating mechanism, the combination with an indicator constructed to be 45 moved from a non-indicating position to an indicating position, of actuating means including a movable device for moving said indicator, the said movable device being constructed to engage the indicator when said indicator is in non-indicating position and, on movement of the actuating means when the indicator is in indicating position, to be moved out of engaging position.

55 17. In an indicating mechanism, the combination with an indicator constructed to be moved from a non-indicating position to an indicating position, of an operating key and a slide carried thereby for moving said indicator, a shoulder projecting from the slide and constructed to hold said slide in engagement with the indicator while the latter is being elevated to indicating position by operation of the key, and a spring for moving 60 the slide and preventing it from contacting

with the indicator when the key is operated while the indicator is in elevated position.

18. In a machine of the class described, the combination with a series of printing counters and a corresponding series of keys 70 for operating said counters separately, of a platen for taking impressions from all of said counters, a bar operated by the keys and to which an operated key becomes locked, said bar receiving a constant movement at each operation of a key, means compelling the full constant movement of said bar said compelling means comprising a member operatively connected to the bar, a rack plate carried by said member, a pair of 75 pawls alternately engaging said plate, and means for oscillating said member upon each operation of the machine thereby bringing the plate into engagement with one or the other of said pawls; means for operating said platen, and devices adapted to be controlled either by said platen operating means for locking the said member of the compelling means against operation and by said member during an operation of a key 80 90 to prevent an operation of said platen operating means.

19. In a machine of the class described, the combination with a printing counter, means including a key for operating said counter, of a platen and means for operating said platen to take an impression of the total on said counter, devices for preventing a second operation of said platen operating means, means adapted to be given a constant movement at each operation of a key and having connections for disabling said preventing devices, and means compelling the complete constant movement of said key-controlled means said compelling means comprising a member operatively connected to said key-controlled means, a frame supporting said member, a rack plate carried by said member, beveled lugs mounted upon the frame, for oscillating the member and the rack plate carried thereby at the end of a movement of said member in both directions, and pawls alternately engaging the rack plate as the same is oscillated.

20. In a machine of the class described, the combination with a printing counter, means including a key for operating said counter, of a platen and means for operating said platen to take an impression of the total on said counter, devices for preventing a second operation of said platen operating means, means adapted to be given a constant movement at each operation of a key and having connections for disabling said preventing devices, and means compelling the complete constant movement of said key-controlled means said compelling means comprising a member operatively connected to said key-controlled means, a frame for 110 120 125 130 guiding said member, a plate carried by the

- member and having ratchet teeth upon the forward and rearward edges thereof, lugs, mounted upon the frame, for oscillating the member and the rack plate carried thereby at the end of the movement of said member in both directions, and pawls mounted upon said frame for alternately engaging the ratchet teeth of the plate as the latter is oscillated, the pawls being arranged to obstruct the oscillatory movement of the plate until the end of movement of the member carrying said plate in either direction.
21. In a machine of the class described, the combination with a plurality of counters and separate operating means for each of said counters, of a platen inking and resetting devices common to all of said counters and common operating means for, first, inking the counters, then, bringing the counters and platen into cooperative relation for taking an impression from all of said counters on a record strip, and finally, operating the resetting devices simultaneously to reset all of said counters.
22. In a machine of the class described, the combination with a plurality of counters and separate operating means for each
- of said counters; of a platen, inking means, and resetting devices common to all of said counters; and common operating means for, first, inking the counters, then, rocking the platen, thereby taking an impression upon a record strip from said counters, and finally operating the resetting devices simultaneously to reset all of the counters.
23. In a machine of the class described, the combination with a plurality of counters and separate operating means for each of said counters; of a platen, inking means, and resetting devices common to all of said counters; and means common to the platen, inking means and resetting devices for first actuating the inking means by movement of the platen then giving the platen an additional movement for taking an impression upon a record strip from all of said counters and finally operating the resetting devices simultaneously to reset all of said counters.

In testimony whereof I affix my signature in the presence of two witnesses.

THOS. CARROLL.
